SIGNATURE-COLLECTING MECHANISM.

1,149,546.

Specification of Letters Patent. Patented Aug. 10, 1915.

Application filed May 7, 1914. Serial No. 836,917.

To all whom it may concern:

Be it known that I, JOSEPH C. THEBERATH, a citizen of the United States, and a resident of Lakewood, county of Cuyahoga, and 5 State of Ohio, have invented a new and useful Improvement in Signature-Collecting Mechanism, of which the following is a specification, the principle of the invention being herein explained and the best mode in 10 which I have contemplated applying that principle, so as to distinguish it from other inventions.

The present improvements relating, as indicated, to signature collecting or gathering 15 mechanism, have particular regard to the provision of an improved signature stuffing machine that will be adapted for use in collecting the parts of newspapers and the like. Particularly in connection with the 20 getting out of Sunday editions, a considerable labor cost is involved in bringing the various "sections" of the paper together.

It is not meant to imply by the foregoing 25 that the present improved mechanism may not be utilized in other connections, either for nesting or stuffing together the various forms of folded sheets of which books, pamphlets and the like are composed, or to stack such sections in a pile, one above the 30 other, as the case may be.

The present invention, then, consists of the means hereinafter fully described and particularly pointed out in the claims.

The annexed drawings and the following 35 description set forth in detail certain mechanism embodying the invention, such disclosed means constituting, however, but one of various mechanical forms in which the principle of the invention may be used.

40 In said annexed drawings:—Figure 1 is a plan view of my improved mechanism with the parts shown in initial or starting position; Fig. 2 is a view similar to Fig. 1, but showing a later operative stage; Fig. 3 is also a view similar to Fig. 1, but showing a still later operative stage; Fig. 4 is a front elevational view of the mechanism as indicated by the line 4—4, Fig. 1; Fig. 5 is a transverse section of the mechanism taken 45 on the vertical plane indicated by the line 5—5, Fig. 1; Fig. 6 is a perspective view of a detail of the mechanism; Fig. 7 is a section of such detail and other associated parts, the plane of the section being indicated by the 50 line 7—7, Fig. 3; Fig. 8 is a top plan view

of the same parts as indicated by the line 8—8, Fig. 7; and Fig. 9 is a sectional view of yet another detail of the mechanism.

Assuming that it is a newspaper composed of several sections that is to be assembled by 60 the mechanism, the sections A and A' will be preliminarily folded and stacked in substantially horizontal position on elevator tables 1 and 2, respectively. These tables are guided in the frame 3 of the machine 65 so as to move vertically and are designed to be raised gradually in any suitable fashion so as to keep the upper surface of the stack in approximately the same horizontal plane and thus on a proper level with respect to 70 the various operating parts of the machine. The arrangement of screws 4 and 5 with bevel gears 6, 6 and 7, 7 connecting the same with drive shafts 8 and 9, may be considered merely typical, since any arrangement, gravity 75 or otherwise, that will accomplish the result just stated, will be equally satisfactory.

The uppermost sections or signatures a and a' of each stack are pressed against stops consisting in each case of a pair of 80 transversely disposed bars 10 and 11 supported from an arm 12 that extends longitudinally across the elevator table, as clearly shown in Figs. 1, 2 and 3. The outermost bar 10 is resiliently connected with the arm 85 by means of compression springs 13, as shown in Figs. 4 and 5, so that if either of said arms is rocked so as to slightly raise their outer ends in the fashion presently to be described, these outermost bars 10 will 90 remain in more or less forceful contact with the stack, while the inner bars 11 are slightly lifted from the stack. To permit of such oscillation of the arms, their inner ends are pivotally attached at 14 to a plate-like portion 15 of the frame that extends transversely across the top of the machine, and intermediately between their respective axes and the innermost pressure bars, each arm is provided with a downwardly projecting pin 95 16, that is adapted to be engaged by the upper edge of a segmental cam 17, as the latter is rotated by a vertical supporting shaft 18. This shaft, which is intergeared with the driving shafts 8 and 9 for elevating the 100 tables 1 and 2, as shown in Figs. 4 and 5, is vertically disposed, being journaled at its upper end in the plate 15 and at its lower end in suitable bearings 19 at the base of the machine frame. Said shaft may be driven 105 110

in any suitable manner, as need not be explained in detail.

In addition to the segmental cam 17 which is supported as just described on this shaft 5 near its upper end, such shaft also supports a disk-like member 20 on which are mounted various operative parts, and below such disk is fixedly supported, as by bars 21 (see Fig. 7), a second cam in the form of a plate 22 having an eccentric groove 23 in its upper face which serves to actuate such operative parts. The latter comprise a sword or finger 24 pivotally attached at 25 to the under side of the disk 20 near its edge, and 10 freely swingable in either direction about its axis, save as limited by a supporting bracket 26 secured to the disk 20 and against which said finger normally rests in the position of parts shown in Fig. 1.

To oscillate the finger, a gear 27 is mounted on the under side of the same disk 20 which supports said finger, such gear meshing with a pinion 28 fixedly secured to the inner end of the finger, and being provided 15 with a rocker arm 29, the free end of which carries a roller 30 that travels in the groove 23 in the cam plate 22. As a result of the foregoing construction, as the shaft 18 rotates, carrying with it the disk and attached 20 parts, the rocker arm 29 trailing the roller 30 in the groove of the cam plate, is oscillated and communicates such oscillation with multiplied effect through the gear 27 and pinion 28 to the finger 24. The form of the 25 groove 23 is such that with the disk and other parts in the angular position about the shaft axis shown in Fig. 1, the finger is entirely retracted, but further rotation of the shaft and disk in the direction indicated by 30 the arrow in said figure, will cause the finger to be projected from the disk 20 in a direction substantially aligned with the retracted position shown in Fig. 1. The result will be to insert such finger between an 35 appropriately disposed section or signature α on the top of the stack A on the adjacent elevator table 1. The continued rotation of the disk is then designed to carry this finger with the signature thus engaged through 40 the arc of a circle until the second stack A' is reached, where the first signature will be inserted or stuffed into the topmost signature α' on said second stack, the latter being appropriately disposed and open for this 45 purpose. A stationary table 31 is located between the two stacks across which the first signature may be thus moved by the finger. Upon reaching the stage of operation just described, the finger 24 is next oscillated so 50 as to be retracted until it again occupies the inoperative position illustrated in Fig. 1.

The segmental cam 17 is so disposed that it will raise the arms 12 respectively just prior to the projecting of the finger 24 outwardly, and just prior to the approach of

the signature α carried by the finger to the topmost signature α' of the second stack A'. The result in the first case is that the topmost section on the first stack, while still held in place by the outer presser bar 10, has 70 its inner edge relieved from pressure so as not to interfere with the insertion of the finger. Similarly, the inner edge of the topmost signature on the second stack is relieved from pressure so as to allow the first 75 signature to be inserted. To facilitate such insertion, it is found desirable to positively open the folded signature in this second stack, and with this object in view a second oscillatory blade or finger 40 is provided, 80 such finger being mounted about a pin 41 depending from the fixed plate 15 that forms a part of the machine frame. This finger is not directly pivotally attached to such pin, but is attached to an arm 42 about a trans- 85 verse axis 47 so that the finger is capable of oscillation both in a horizontal and a vertical plane. The arm, and thus the finger, are normally positioned in a horizontal plane by means of a coil-spring 43 which tends to 90 retain the arm against a stop 44 depending from the same plate, while a second spring 45, that connects the arm 42 and rear extension 48 of the finger 40 tends to retain the latter in its normal depressed position. The 95 outer face of the segmental cam 17, however, is designed to engage the end of the arm and swing the same from the position shown in Fig. 1 to that shown in Fig. 3, and there maintain the same until said cam has 100 entirely passed. Such oscillation of the arm serves to swing the finger from the position shown in Fig. 1 to that shown in Fig. 3, or in other words to insert such finger, which is in the form of a very thin blade, between 105 the topmost folded section or signature on the second stack. During the period of engagement of the arm by the cam, the rear extension 48 of the finger, which latter is oscillatory in a vertical plane as previously 110 described, is engaged by an inclined rib 46 on the face of the cam 17 so as to depress such rear extension and thereby raise the finger proper against the spring 45, the finger being shown in such raised position in 115 Fig. 7. The effect of this action is to open the folded signature so as to permit of the ready insertion of the signature carried by the first finger 24.

Either in conjunction with such second 120 finger, or independently thereof, I may also utilize a suction device 50 shown in detail in Fig. 9, so disposed as to engage the inner forward corner of the topmost section on the second stack. As shown in Fig. 9, this device comprises simply a tube 51 open at its lower end and having a reciprocable piston 52 which is adapted to be raised by one and depressed by the other of two aligned solenoids 53 and 54 which surrounds an arma- 125 130

ture 55 to which the piston is secured. The electrical connections to such solenoids are controlled by means of suitable contacts (not shown) carried by the disk 20, or other part 5 rotating synchronously with the shaft 18, so that the piston may be raised at the proper time to lift the adjacent corner of such topmost section preliminarily to the insertion therein of the section being carried over 10 from the first stack.

10 Adjacent to the further side of the second elevator table suitable belt conveyers 60 or like means are provided for removing the collected sections, the finger 24 being designed to shift the topmost section α in 15 which the filler section α has been placed in the manner just described, sufficiently to cause such collected section and filler to be engaged by the conveyer. From the conveyor the collected sections may be deposited 20 in a hopper 61 as shown in the several figures of the drawings.

25 The general operation of my improved mechanism should be evident from the foregoing description of the construction of its component parts and their individual operation. It will be seen that no parts of a complicated nature are involved, and all are furthermore readily accessible for adjustment, and such other attention as may be required. The machine is thus adapted particularly for use in newspaper offices and the like, where hard service is in store for it. At the same time the same principle of operation may be advantageously used in machines designed for collecting or stacking 35 signatures in regular pamphlet and book-printing establishments.

40 Other modes of applying the principle of my invention may be employed instead of the one explained, change being made as regards the mechanism herein disclosed, provided the means stated by any of the following claims or the equivalent of such stated 45 means be employed.

I therefore particularly point out and distinctly claim as my invention:—

1. In mechanism of the character described, the combination of means for supporting a stack of folded sheets, a second support, a member adapted to move a folded sheet from said stack to said second support, means for causing said member to enter between the folded portion of a sheet 50 and move it to said second support, and means for thereafter laterally withdrawing said member to disengage it from the sheet.

2. In mechanism of the character described, the combination of a support for a 55 stack of folded sheets; a second support; a member mounted adjacent to said supports, and adapted to enter between the leaves of a sheet on such stack, said member being oscillatable thus into and out of engagement 60 with a sheet on such stack, and rotatable to

transfer the engaged sheet to the second support; and means for simultaneously rotating and oscillating the member.

3. In mechanism of the character described, the combination of a support for 70 a stack of folded sheets; a second support; a member mounted adjacent to said supports and adapted to enter between the leaves of a sheet on such stack, said member being oscillatable about one axis thus into and out of engagement with a sheet on such stack, and rotatable about a second axis to transfer the engaged sheet to the second support; and means for simultaneously rotating and oscillating the member. 75

4. In mechanism of the character described, the combination of supports for a plurality of stacks of folded sheets, means for opening a folded sheet on one stack, a member adapted to enter between the fold 80 and transfer the sheet to another stack, means for laterally moving said member into and out of engagement with a sheet, and means for moving said member for transferring the sheet. 85

5. In mechanism of the character described, the combination of two supports each adapted to support a stack of folded sheets, a member for engaging and moving a sheet from one support to the other, means 90 for swinging said member for effecting the transfer, and means for moving said arm into and out of engagement with the sheet. 95

6. In mechanism of the character described, the combination of two supports 100 each adapted to support a stack of folded sheets; means for opening a folded sheet on one stack; a member mounted adjacent to said supports and adapted to enter between the leaves of a sheet on either of said stacks, 105 said member being oscillatable about one axis into and out of engagement with a sheet on the other such stack, and rotatable about a second axis to transfer and insert the engaged sheet in the open sheet on such first 110 stack; and means for simultaneously rotating and oscillating the member.

7. In mechanism of the character described, the combination of a support for a 115 stack of folded sheets; a support for a second stack of sheets; a rotatable support; a finger pivoted on said last-named support on an axis parallel with its axis of rotation, said finger being adapted to enter between the leaves of and thus engage a sheet on either of said stacks; and means for rotating said last-named support and oscillating the finger on its pivotal axis. 120

8. In mechanism of the character described, the combination of a support for 125 a stack of folded sheets; a support for a second stack of sheets; a rotatable support; a finger pivoted on said last-named support on an axis parallel with its axis of rotation, said finger being adapted to enter between 130

the leaves of and thus engage a sheet on either of said stacks; a cam fixedly mounted adjacent to said last-named support; a lever pivoted to said last-named support and engaging said cam; and mechanism connecting the lever and finger to oscillate the latter upon oscillation of the former.

9. In mechanism of the character described, the combination with a substantially horizontal table adapted to carry a stack of folded sheets; of sheet opening means including a stationary support laterally adjacent to said table; a finger mounted thereon so as to be oscillatory about a vertical and a horizontal axis; and means adapted to successively oscillate said finger about such axes in the order named.

10. In mechanism of the character described, the combination with a substantially horizontal table adapted to carry a stack of folded sheets; of sheet opening means including a stationary support laterally adjacent to said table; a finger mounted thereon so as to be oscillatory about a vertical and a horizontal axis; means normally positioning said finger about such axes, respectively; and means adapted to successively oscillate said finger about such axes in the order named.

11. In mechanism of the character described, the combination with a substantially horizontal table adapted to carry a stack of folded sheets; of sheet opening means including a stationary support laterally adjacent to said table; an arm mounted thereon so as to be oscillatory about a vertical axis; a finger pivotally attached to said arm about a horizontal axis; and a movable cam adapted successively to engage said arm and finger and oscillate the same about such axes, respectively.

12. In mechanism of the character described, the combination with a substantially horizontal table adapted to carry a stack of folded sheets; of sheet opening means including a stationary support laterally adjacent to said table; an arm mounted thereon so as to be oscillatory about a vertical axis; a finger pivotally attached to said arm about a horizontal axis; springs normally positioning said arm and finger, respectively; and a rotatable cam having faces adapted successively to engage said arm and finger and oscillate the same about such axes, respectively.

13. In mechanism of the character described, the combination with two elevator tables respectively adapted to support a stack of folded sheets with the topmost sheet of each stack in approximately the same horizontal plane; a vertical rotary shaft adjacent to said tables; a pivoted finger eccentrically carried by said shaft so as to be oscillatory in the plane of such topmost sheets, said finger being adapted to engage and transfer a sheet from one stack to the other; means adapted to oscillate said finger as said shaft rotates; a relatively fixed support adjacent one of the tables; and a finger mounted thereon so as to be oscillatory about both a horizontal and a vertical axis, said last mentioned finger being adapted to enter between the folds of a sheet and open same for the purpose specified.

14. In mechanism of the character described, the combination with two elevator tables respectively adapted to support a stack of folded sheets with the topmost sheet of each stack in approximately the same horizontal plane; a vertical rotary shaft adjacent to said tables; a pivoted finger eccentrically carried by said shaft so as to be oscillatory in the plane of such topmost sheets, said finger being adapted to engage and transfer a sheet from one stack to the other; means adapted to oscillate said finger as said shaft rotates; a relatively fixed support adjacent one of the tables; and a finger mounted thereon so as to be oscillatory about both a horizontal and a vertical axis, said last mentioned finger being adapted to enter between the folds of a sheet and open same for the purpose specified.

15. In mechanism of the character described, the combination with two elevator tables respectively adapted to support a stack of folded sheets with the topmost sheet of each stack in approximately the same horizontal plane; a vertical rotary shaft adjacent to said tables; a pivoted finger eccentrically carried by said shaft so as to be oscillatory in the plane of such topmost sheets, said finger being adapted to engage and transfer a sheet from one stack to the other; means adapted to oscillate said finger as said shaft rotates; a relatively fixed support adjacent one of the tables; a finger mounted thereon and adapted to enter between the folds of a sheet and open same for the reception of another sheet, said finger being oscillatory about both a horizontal and a vertical axis; and a segmental cam carried by said shaft and adapted successively to oscillate said finger about such axes in the order named.

16. In mechanism of the character described, the combination with two elevator tables respectively adapted to support a stack of folded sheets with the topmost sheet of each stack in approximately the same horizontal plane; a vertical rotary shaft adjacent to said tables; a pivoted finger eccentrically carried by said shaft so as to be oscillatory in the plane of such topmost sheets, said finger being adapted to engage and transfer a sheet from one stack to the other; means adapted to oscillate said finger as said shaft rotates; a relatively fixed support adjacent one of the tables; a finger mounted thereon and adapted to enter between the folds of a sheet and open same for the reception of another sheet, said finger being oscillatory about both a horizontal and a vertical axis; and a segmental cam carried by said shaft and adapted successively to oscillate said finger about such axes in the order named.
